HEAT EXCHANGER

Hugo Merta, La Crosse, Wis.

Application April 12, 1935, Serial No. 15,940

5 Claims. (Cl. 257—248)

My invention relates to an improvement in heat exchangers.

One of the objects of my invention is to provide means for allowing the expansion of a heat exchanger composed of headers and tubes without allowing a lateral movement of the headers.

Another object of my invention is to prevent the torsion of the tubes by any movement of the headers other than in the longitudinal direction of the tube.

Another object of my invention is to allow the free expansion of the tubes and the headers of the heat exchanger without subjecting them to shearing strains.

The various features of novelty which characterize my invention are pointed out in claims annexed to and forming a part of this specification.

In the accompanying drawing which illustrates my invention, Figure 1 is a side elevation of a corner of the heat exchanger.

Figure 2 is a vertical sectional elevation of a corner of the heat exchanger taken on the line 2—2 of Figure 1.

Figure 3 is a vertical elevation of the heat exchanger.

Referring to Figure 3, 1 represents the heat exchanger composed of headers 2 connected by tubes 3, on which are mounted fins 4. On the sides of the heat exchanger are the channel bars 13 extending between the headers 2. The channel bars 13 are connected by the reinforcing bars 12, which extend across the heat exchanger and connect the opposite channel bars 13. The channel bars 13 protect the fins 4 and with the reinforcing bars 12 form a support for the tubes 3. These channel bars 13 are not normally fastened either to the fins or to the tubes, or header, but float so as to allow free expansion and contraction of the tubes. However, without detracting from their efficiency, one end of the channel bars may be affixed to one of the headers.

Referring to Figure 2, the angle bar 5 is fastened rigidly to the headers 2 by the bolt 10, which extends through the header 2 and the end wall 6 of the angle bar 5. The channel bars 13 comprise the bottom 9 and the side walls 7 and 8 of said channel. The angle bar 5 fits along the bed 9 of the channel section and fully occupies the bed of the channel section so that the side of the angle bar 5 contacts the side walls 7 and 8 of the channel section 13.

15 is a spacer angle which is sheet metal formed up on three sides, making four sides, to wit: sides 16, 17, 18 and 19. The sides 16 and 17 are

spot-welded to the side walls 8 and 7, respectively, of the channel section 13 and the wall 18 abuts against the angle iron 5 so as to allow movement of the angle iron 5 between the wall 18 and the bed of the channel 9 longitudinally with respect to the tubes 3, but the angle 5 is prevented from moving in any other direction by the wall 18, wall 9, and the side walls 7 and 8. The angle 5 is made out of stiff metal material rigidly attached to the headers 2. In connecting these heat exchangers to heating or cooling systems, the pipe connections leading to these heat exchangers are frequently of considerable length and the expansion and contraction of the pipes tend to cause a movement of the headers lateral with respect to the tubes. Also, when the headers are held in a fixed position by the aforesaid connecting pipes, the expansion of the tubes 3, due to heat or cold, frequently tend to cause a lateral movement of the headers with respect to the tubes. It is desirable, therefore, in order to prevent shearing strains and stresses on the tubes, which are of light material, to allow the headers 2 to move only longitudinally with respect to the tubes 3 and to prevent any movement of the 25 headers laterally.

It may be seen that angle means may be used instead of the side walls 7 and 8 to prevent the lateral movement of the angle bars 5.

Although one specific embodiment of the invention has been particularly shown and described, it will be understood that the invention is capable of modification and that changes in the construction and in the arrangement of the various co-operating parts may be made without departing from the spirit or scope of the invention, as expressed in the following claims:

What I claim is:

1. In a heat exchanger the combination of opposite headers connected by metal tubes with fins mounted thereon, channel sections secured together and extending between said headers, and angle bars fastened to said headers and co-operating with the first named channel sections to allow movement of said headers only longitudinally with respect to said tubes.

2. In a heat exchanger the combination of opposite headers connected by metal tubes with fins mounted thereon, channel sections extending between said headers on the side of said exchanger, and angle bars fastened to said headers and co-operating with the first named channel sections to allow movement of said headers only longitudinally with respect to said tubes.

3. In a heat exchanger the combination of

opposite headers connected by metal tubes with fins mounted thereon, side plates extending between said headers on the side of said exchanger, and angle bars rigidly secured to said headers and co-operating with the said side plates to allow movement of said headers only longitudinally with respect to said tubes.

4. In a heat exchanger the combination of opposite headers connected by metal tubes with fins mounted thereon, side plates extending between said headers on the side of said exchanger, plates rigidly attached to said headers and arranged to slide on the first named plates, and

angle means mounted on one of said side plates to allow movement of said plates, attached to the headers, only longitudinally with respect to said tubes.

5. In a heat exchanger the combination of opposite headers connected by metal tubes with fins mounted thereon, side plates extending between said headers on the side of said exchanger, and means rigidly attached to said headers co-operating with said plates to allow movement of said plates only longitudinally with respect to said tubes.

HUGO MERTA.
